(57) **CLAIM**

The ornamental design for a tablet, as shown and described.

DESCRIPTION

FIG. 1 is a perspective view of an imprinted surface indicia for a tablet showing my new design;

FIG. 2 is a top view of the tablet of FIG. 1;

FIG. 3 is a cross sectional view of the tablet taken along line 3—3 of FIG. 1;

FIG. 4 is a perspective view of an alternate embodiment of the surface indicia for a tablet according to my new design; and,

FIG. 5 is a top view of the tablet of FIG. 4.

The broken lines in the figures merely illustrate the environment for the tablet of the present design and therefore form no part of the claimed design.
